[57] CLAIM

The ornamental design for a snow and ice scraper and brush unit, as shown and described.

DESCRIPTION

FIG. 1 is a left side elevational view of a snow and ice scraper and brush unit embodying our design, the broken lines representing the brush are for illustrative purposes only and therefore form no part of the claimed design, with the right side elevational view of the scraper and brush unit being a mirror image thereof;

FIG. 2 is a top plan view of the snow and ice scraper and brush unit;

FIG. 3 is a bottom plan view of the snow and ice scraper and brush unit, with the brush being illustrated in broken lines for the reasons noted above;

FIG. 4 is a front elevational view of the snow and ice scraper and brush unit, with the brush being illustrated in broken lines for the reasons noted above; and,

FIG. 5 is a rear elevational view of the snow and ice scraper and brush unit, with the brush being illustrated in broken lines for the same reasons noted above.
